UNITED STATES PATENT OFFICE

125,346

DESIGN FOR SHORTS OR SIMILAR ARTICLE

Helen A. Myron, Beverly Hills, Calif.

Application November 30, 1940, Serial No. 96,975

Term of patent 7 years

To all whom it may concern:

Be it known that I, Helen A. Myron, a citizen of the United States, residing at 8938½ Burton Way, Beverly Hills, in the county of Los Angeles, State of California, have invented a new, original, and ornamental Design for Shorts or Similar Article, of which the following is a specification, reference being had to the accompanying drawing, forming part thereof.

Fig. 1 is a front elevational view of shorts showing my new design;

Fig. 2 is a side elevational view thereof;
Fig. 3 is a view similar to Fig. 2 with the back flap partly turned back and the front flap folded downwardly; and

Fig. 4 is a rear elevational view of Fig. 1 with the back flap turned down.

I claim:

The ornamental design for shorts or similar article, as shown,

HELEN A. MYRON.
